(57) **CLAIM**

The ornamental design for a motorcycle, toy, and/or replicas thereof, as shown and described.

DESCRIPTION

FIG. 1 is a left, front perspective view of a motorcycle, toy, and/or replicas thereof according to the design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The portions in the drawings that are shown in a light tonal contrast illustrate portions of the motorcycle, toy, and/or replicas thereof that form no part of the claimed design.

1 Claim, 7 Drawing Sheets
